UNITED STATES PATENT OFFICE.

JULES F. HANCOCK AND CARROLL E. FISK, OF SAN FRANCISCO, CALIFORNIA.

LABEL-MOISTENING MACHINE.

1,081,906.

Specification of Letters Patent.

Patented Dec. 16, 1913.

Application filed March 29, 1913. Serial No. 757,718.

To all whom it may concern:

Be it known that we, JULES F. HANCOCK and CARROLL E. FISK, citizens of the United States, residing in the city and county of San Francisco, State of California, have invented certain new and useful Improvements in Label-Moistening Machines, of which the following is a specification.

Our invention relates to label moistening machines and more particularly for those designed to use the ribbon type of labels. These labels are printed on a continuous strip of gummed paper adapted to be used in my machine and in this form reduce the cost of printing and handling, as they come from the press in the form of a roll.

The object of our invention is to provide a machine that will handle a roll of gummed labels without an axis, provide a place for the clerk to write the directions, address, or instructions thereon, moisten the same and shear off the label at a given point.

It will be readily seen that our invention is a time and labor saving device as well as reducing the cost of the label itself by providing a means for using it in the ribbon form.

For a clear comprehension of our invention reference should be had to the accompanying drawing, in which:—

Figure 1, is a side view in elevation of the device with one side broken away to show the roll of printed labels in place. This view also shows the spring supported feed roller frame holding the gummed label away from the moistening roll when not in use. The dotted line at the back shows the spring trap door open to allow the roll of labels to be placed in the machine. Fig. 2, is a plan view of the device showing a strip of labels in place and the convenient manner in which they may be inscribed before moistening and shearing. Fig. 3, is a view in cross-section of the upper part of the device showing the relative position of the spring supported feed roll to the moistening roll in its reservoir. This view also shows the triangular shearing bar in front of the feed roll and the double guide bars back of the same. The view is taken on the line X, X, Fig. 2.

The numeral 1, is used to designate a frame or cage adapted to receive the roll of printed and gummed labels 2, and retain the same therein by means of the spring trap door 3. The spring supported frame

4, is pivotally mounted on the cage 1, and the feed roller 5, is rotatably mounted in the free end thereof.

6, is a triangular shearing bar and 7, 7, 60 are the guide bars to the feed roll 5. The springs 8, 8, support the feed roller frame and serve to hold the gummed label away from the moistening roller 9. At the back of the cage is another guide bar 10, which 65 serves to keep the label strip flat on the table plate 11. This table plate is made of aluminum as the gummed side of the labels come into contact with the same and will not adhere to this metal. The reservoir 12, 70 carries the water for the moistening roll 9, and is provided with the plate 13, which forms a cover to prevent the label from entering the reservoir as it comes through the rolls. The pads 14, 14, may be of any 75 suitable material that will prevent the machine from marring the surface of the table or counter on which it is being operated.

The operation of our invention is as follows:—The roll of printed labels is placed 80 in the cage and the spring door retains the same in place. The end of the strip is then passed under the first guide bar, drawn on the table and entered between the guide bars in the spring supported frame, under 85 the first and over the second, thus keeping the paper in contact with the feed roll and shearing bar. In this position it is free from contact with the moistening roll. After the label has been properly inscribed 90 the operator presses the feed roller down with the fingers or palm of the hand until the gummed side of the label comes into contact with the moistening roller; the movement of the hand toward the back of 95 the machine causes the feed roller to rotate in the direction indicated by the arrow (Fig. 3) thus discharging the label between the two rolls to any extent desired. The operator holding the feed roll in the above 100 described position can then tear the label neatly and quickly across the edge of the triangular shearing bar. In the process of discharging, the moistening roller applies the water to the gum of the label and the 105 same is ready to be attached to the parcel for which it is intended.

We do not wish to be understood as confining ourselves to the precise construction shown herein, but wish to avail ourselves of 110 any modifications that may properly fall within the scope of our invention.

Having thus described our invention, what we claim as new and desire to secure by Letters Patent, is:—

In combination in a label moistening machine, a support for a roll of labels, a table over which the label strip passes in exposed condition, a moistening roll at one end of the table, a feed roll above the moistening roll, a normally elevated spring support for the feed roll with guide means thereon for the paper, said spring support with its guide means holding the paper above and separated from the moistening

roll normally but allowing said paper to remain in contact with the table, said feed 15 roll, when pressed down, forcing the paper upon the moistening roll and permitting the paper to be fed between it and the moistening roll, substantially as described.

In testimony whereof, we affix our signatures in presence of two witnesses.

JULES F. HANCOCK.
CARROLL E. FISK.
